UNITED STATES PATENT OFFICE

MATHIAS PIER, OF HEIDELBERG, GERMANY, ASSIGNOR, BY MESNE ASSIGNMENTS, TO STANDARD-I. G. COMPANY, OF LINDEN, NEW JERSEY, A CORPORATION OF DELAWARE

DESTRUCTIVE HYDROGENATION OF CARBONACEOUS MATERIALS

Original application filed October 27, 1927, Serial No. 229,084, and in Germany August 7, 1926. Divided and this application filed August 28, 1928. Serial No. 302,639.

This application is a divisional application and relates to subject-matter which has been divided out from my copending application for Patent Ser. No. 229,084 filed October 27th, 1927.

The present invention relates to the manufacture of valuable hydrocarbons and derivatives by the destructive hydrogenation of carbonaceous materials, such as the various kinds of coal, tars, mineral oils and distillation, extraction and conversion products and residues thereof and the like, that is the treatment of the said materials with hydrogen or gases containing or giving off hydrogen, at elevated temperatures and under a high pressure of 50 atmospheres or more of the hydrogenating gas, in the absence or presence of catalysts.

I have now found that if initial materials are employed, which are free from sulfur or its compounds the reaction vessel, and preferably also the other parts of the apparatus which come into contact with the hot organic reacting material may be constructed of or lined with copper or alloys thereof. Otherwise spongy sulfurous masses are formed which lead to rapid corrosion of the apparatus and which moreover cause deposition of carbon and formation of methane. Accordingly care must be taken that the reaction vessel including the catalyst, the walls of the vessel and, if such be arranged therein, the heating devices, and preferably also the other hot parts of the apparatus such as the pipings, heat regenerators and the like which come into contact with the organic reacting materials, are free from such substances as would cause the said obnoxious by-reactions. It is also necessary to prevent the initial materials and especially the gases from conveying obnoxious substances into the reaction vessel or the other hot parts of the apparatus.

The apparatus may also in part be constructed of or coated with alloys containing cobalt, molybdenum, tungsten, vanadium or manganese, or several of these elements and in addition thereto, if desired, a considerable percentage of nickel, in particular highly al-

loyed steels containing the said elements or with silver or alloys thereof.

These parts of the apparatus which come into contact with hot organic materials may also be provided with a content in certain metalloids such as boron, arsenic, antimony, silicon, bismuth, phosphorus, selenium and the like. These metalloids may be alloyed with the metals, or they may be incorporated only with the surfaces thereof, for example by the action of compounds of the said metalloids on the surfaces of the apparatus. Also by this means the formation of methane and the separation of carbon are considerably reduced.

Such metals and alloys are also very suitable for construction of parts of the apparatus in which the boundaries of the crystal grains are substantially free from impurities as can be determined by microscopic examination. By such absence of impurities a stable crystal structure is obtained, as a consequence of which the material is not attacked even when the apparatus is subjected to a very severe treatment for a very long period. In some cases, such substantially pure metals or alloys are attacked but such attack takes place only superficially, and accordingly, when the superficial layer which has been exposed to attack, peels off, a smooth surface free from pores is formed again which does not give rise to any obnoxious additions, whereas with the usual metals entire structure would be loosened and accordingly the material would become porous. In the case of the said superficial attack of the metals or alloys free from impurities, the surface thereof may be kept clean and suitable for working in any suitable way, for example, by scraping. Metals and alloys which have been prepared by fusion in vacuo are particularly suitable as they are particularly free from the said impurities in the boundaries of the crystal grains.

I have further found that the said materials which do not give rise to the formation of methane and separation of carbon may also be employed as catalysts in the process according to my present invention. It is advantageous to employ catalysts with a large

and preferably smooth surface. For this purpose the catalysts may be constructed in any suitable manner for example they may be sheets or wires which may be heated to the temperature of the reaction for example by electric resistance heating. Catalysts of this kind are distinguished by their excellent stability in continued use. In order to keep the catalytically acting surfaces clean and 5 smooth, it is advantageous to maintain a high speed of the reacting materials or gases so that a great relative movement between the catalytic surfaces and the reacting materials is established. This may be furthered by mechanically setting the catalysts into movement.

The initial materials may be employed in a solid or liquid and preferably in a finely divided, for example atomized, state, or in 10 the form of vapor. It is advantageous to work with the hydrogenating gas in a circulatory course and to provide an intimate contact of the said hydrogenating gas with the materials to be treated for example by 15 employing the latter in the form of thin layers or by stirring, atomizing and the like.

The process according to the present invention is preferably carried out with a large excess of hydrogenating gas and with streaming gases, the reaction vessel, and preferably 20 also the other parts of the apparatus which come into contact with the hot organic reacting material being kept free from such substances as would give rise under the conditions of working to the formation of methane and deposition of carbon.

The process according to this invention is especially suitable for the production of valuable liquid fuels such as benzine, heavy oils 25 for Diesel engines and the like, for the production of benzene and its homologues and also in the manufacture of valuable lubricants, solvents and the like.

45 The present invention will be further described with reference to the accompanying drawing representing in a diagrammatic manner a vertical section of an apparatus especially suitable for carrying out this invention which, however, is not restricted thereto.

Referring to the drawing in detail numeral 11 denotes a hydrogenating vessel, the wall 1 of which is coated with a lining 12 consisting of copper. The initial material, free 50 from sulphur, is introduced at 7 into the heat regenerator 3 and is heated in coil 8 surrounding tubes 5 through which tubes hot materials issuing from the destructive hydrogenation are flowing. The preheated materials then pass through pipe 9 and are heated to the reaction temperature in the heating coil 13; they enter the hydrogenating 55 vessel at 10.

What I claim is:

1. In the destructive hydrogenation of carbonaceous materials at pressures of at least 50 atmospheres of hydrogenating gas in apparatus the inner surfaces of which are constructed wholly or in part of copper or alloys thereof the step which comprises excluding sulphur and its compounds from the material under treatment. 70

2. In the destructive hydrogenation of carbonaceous materials at pressures of at least 50 atmospheres of hydrogenating gas in apparatus the inner surfaces of which are constructed wholly or in part of copper or alloys thereof the step which comprises excluding sulphur and its compounds from the material under treatment and operating in streaming gases with a large excess of the hydrogenating gas. 75

3. In the destructive hydrogenation of carbonaceous materials at pressures of at least 50 atmospheres of hydrogenating gas in apparatus, the inner surfaces of which are constructed at least in part of copper or alloys thereof, the step of operating with initial 80 materials which are free from sulphur and its compounds. 85

4. In the destructive hydrogenation of carbonaceous materials at pressures of at least 50 atmospheres of hydrogenating gas in apparatus the inner surfaces of which are constructed at least in part of copper or alloys thereof, the step of operating with initial 90 materials which are free from sulphur and its compounds and operating with a large excess of streaming hydrogenating gas. 100 95

In testimony whereof, I affix my signature.
MATHIAS PIER.
